LOCK

Norman B. Hurd, New Britain, Conn., assignor to
 The American Hardware Corporation, New
 Britain, Conn., a corporation of Connecticut

Application December 15, 1928, Serial No. 326,207
 Renewed August 23, 1930

22 Claims. (Cl. 70—91)

This invention relates to locks and latches, particularly of the type in which a key mechanism, such as a pin cylinder lock, is used within one of the knobs to turn a lock and/or latch operating spindle, which passes inwardly through the knob shank. It is of further importance in connection with such locks and latches as embody mechanism mounted on and cooperating with the knob shank. The invention primarily resides in a construction which permits the cylinder lock mechanism contained within the knob to be quickly and easily removed by a mechanic, not necessarily skilled in the lock art, so that another cylinder, adapted to be operated by a different key, may be substituted. In most locks of the type referred to, to substitute one cylinder for another within the knob mechanism involves not only considerable labor, but also requires a skilled mechanic. My present invention is of importance in that it reduces substantially the time required to change the cylinder, and also obviates the necessity of employing a lock expert for that purpose. The purpose of this invention may be better understood when it is appreciated that in large apartment houses and office buildings, wherein a great number of such locks are employed, the occupants of the apartments and offices are frequently changed, so that it becomes necessary to provide each new tenant with a different key. The present invention permits this to be easily and quickly done without disturbing the main lock mechanism in the slightest and without even opening the door on which the lock is mounted. In the present invention, the knob and knob shank construction are such that the knob, or a portion thereof, may be detached from the shank without disturbing the position of the latter, whereby, when this is done, an entirely new cylinder lock element may be quickly and easily substituted for the old one.

In the form shown herein the removable knob portion is locked to and unlocked from the balance of the knob by means of a special key, which may be kept by the one in charge of the building containing the offices or apartments.

In the accompanying drawing, which shows my invention in one of its preferred forms—

Fig. 1 is, in the main, a longitudinal section of a door knob and associated parts, constructed to embody my invention;

Fig. 2 is an end view of one of the parts;

Fig. 3 is an end view of other parts, partly assembled;

Fig. 4 is an end view of certain details, partly assembled;

Fig. 5 is a view similar to Fig. 1, but showing certain parts in a different position, and also showing a different key from that illustrated in Fig. 1;

Fig. 6 is a longitudinal sectional view partly broken away, taken on a plane at right angles to that of Fig. 5;

Fig. 7 is a perspective view of a detail.

1 represents a knob shank having a flange 1^a, which in the form shown constitutes a part of the door knob. 2 is the other part of the knob which is arranged to screw onto the part 1^a, the screw thread being shown at 2^a. When the two parts of the door knob are assembled, a hollow space is formed therein in which is located a key-controlled device in the form of a cylinder lock 3, the outer end of said lock being accessible at the central outer end of the knob so that a key 4 may be inserted to operate the pin tumblers, whereby the plug 5 of said cylinder lock may be turned to rotate the usual spindle 6 secured to the inner end of the plug in any suitable manner, and by which any appropriate lock and/or latch mechanism (not shown) may be actuated. The knob shank 1 may co-operate with any suitable door latch or lock mechanism, the construction of which is not essential to this invention, and hence is not shown. It will be observed that the key 4, which I will term the pass key, operates all of the pin tumblers excepting the innermost one 12, this latter being employed for a special purpose. When the key 4 is in place, the plug 5 may be turned to rotate the spindle 6 and actuate any mechanism that may be associated therewith. Inasmuch as the key-controlled device is located within the hollow knob, it is, of course, important that the two separable parts thereof must be locked together not only so that the shank of the knob may be turned when the hand is applied to the outer knob section 2, but also because the key-controlled device within the knob must be properly held and supported therein and retained against removal excepting by one having the authority to remove it for repair or substitution. To that end I provide devices within the knob, which, when the separable sections thereof are connected together, are moved so as to lock said sections so that they cannot be disconnected one from the other. This knob locking mechanism I will now describe.

In the opposite inner edges of the screw 55

threaded portion of the part 1^a, I provide two diametrically positioned recesses forming guide slots for receiving two sliding locking dogs 7—7, which in Fig. 3 are shown as standing retracted 5 in said slots. In the knob section 2, I provide two recesses 8—8, which, when the knob sections are assembled, face up with the dogs 7—7, so that when the latter are projected into said recesses 8—8, the two parts 1^a and 2 of the 10 knob cannot be unscrewed or otherwise disconnected. In order to move the dogs 7—7, I provide a controlling device 9 having a hub which is rotatably mounted on the inner end of the plug 5, said rotatable device having a flanged portion in which are two angularly arranged cam grooves 9^a—9^a. On one side face of each dog 7 is a pin or stud 10, which, when the parts are 15 assembled, stands in its respective cam groove 9^a, as indicated in Figs. 3, 4 and 6.

20 Referring particularly to Fig. 3, it will be seen that if the controller 9 is rotated counter-clockwise from the position shown in Fig. 3, it would tend to project the dogs 7—7 into the recesses 8—8 of the part 2 thus locking the knob parts together. Normally, the controlling device 25 9 is locked by tumbler 12 to the cylinder 3, as shown in Fig. 1, and is unlocked from the plug 5, so that when a key such as the key 4 is inserted said plug may be turned to rotate the 30 spindle 6 without turning the controller 9. When, however, it is desired to operate said controller, a special master-key 15 is used, this key being adapted to operate all of the pin tumblers as shown in Fig. 5. When this key is used, it 35 moves tumbler 12 to a position where it locks the controller 9 to the plug and releases it from the cylinder 3. Under this last condition, it is obvious that by turning the key 15 the controller 9 may be correspondingly turned, by which 40 turning movement the dogs 7—7 may be projected or retracted for the purpose previously described. In the particular form shown, it will be understood that the controller 9 is partly cut away on one side, as at 14, to afford 45 clearance for the pin chamber 3^a of the pin cylinder lock.

While I have shown and described herein a key-controlled device of the pin cylinder type in which a flat key is employed, my invention is not necessarily limited to that specific form 50 of lock, as other types might be employed, the main purpose being to provide in the construction of this lock a key-controlled device within a hollow knob, accessible through the outer end 55 of the knob, whereby, by the use of one key, the lock mechanism such as the spindle 6 may be operated under normal conditions, and whereby by the use of another key insertible into said device the knob locking mechanism may be 60 actuated so that the knob may be separated to permit the key-controlled device to be changed or repaired as desired.

I claim:

1. A hollow door knob including two separable 65 parts, means for causing said parts to be engageable and disengageable by rotation of one relatively to the other, locking means within said knob to prevent relative rotation of said parts when assembled, door lock operating means also 70 associated with said knob, and key controlled means also within said knob and operable by the rotation of one key to operate the door lock operating means and by the rotation of another key to operate the knob locking means.

75 2. A hollow door knob including two separable

parts, means for causing said parts to be engageable and disengageable by rotation of one relatively to the other, knob locking means within said knob to prevent relative rotation of said parts when assembled, door lock operating means 5 also associated with said knob, and key controlled means also within said knob and operable by the rotation of one key to operate the door lock operating means and by the rotation of another key to operate the knob locking means, the outer 10 section of said separable knob having a key passage in the outer end thereof.

3. A hollow door knob including two separable parts, means for causing said parts to be engageable and disengageable by rotation of one 15 relatively to the other, knob locking means within said knob to prevent relative rotation of said parts when assembled, door lock operating means also associated with said knob, and key controlled means also within said knob and operable by the rotation of one key to operate the door lock operating means and by the rotation of another key to operate the knob locking means into and out of knob locking position, the outer section of said separable knob having a 25 passage in the outer end thereof for receiving either of said keys.

4. A hollow door knob including two separable parts, means for causing said parts to be engageable and disengageable by rotation of one 30 relatively to the other, knob locking means within said knob to prevent relative rotation of said parts when assembled, door lock operating means also associated with said knob, and key controlled means also within said knob and operable 35 by one key to operate the door lock operating means and by another key to operate the knob locking means, said key controlled means including a rotatable plug and a series of pin tumblers, said knob locking means being mounted on said plug and lockable thereto and unlockable therefrom by one of said tumblers.

5. A hollow door knob including two separable parts, means for causing said parts to be engageable and disengageable by rotation of one 40 relatively to the other, knob locking means within said knob to prevent relative rotation of said parts when assembled, door lock operating means also associated with said knob, and key controlled means also within said knob and operable 45 by the rotation of one key to operate the door lock operating means and by the rotation of another key to operate the knob locking means, said knob locking means including a movable dog carried by one of said knob parts and engageable with and disengageable from the other knob part.

6. A hollow door knob including two separable parts, means for causing said parts to be engageable and disengageable by rotation of one relatively to the other, knob locking means within said knob to prevent relative rotation of said parts when assembled, door lock operating means also associated with said knob, and key controlled means also within said knob and operable 55 by the rotation of one key to operate the door lock operating means and by the rotation of another key to operate the knob locking means, said knob locking means including a movable dog carried by one of said knob parts and engageable with and disengageable from the other knob part, and a controller operated by the last mentioned key, for operating the said dog.

7. In a lock, a lock cylinder, a substantially radially movable member for locking said cylin- 75

- der to a door, a plug in said cylinder, said plug being formed in two relatively movable parts, and means actuated by one of said relatively movable parts for actuating said radially movable member.
- 5 8. In a lock, a lock cylinder, a substantially radially movable member for locking said cylinder to a door, and key-operable means for operating a door locking means by the use of one key and for actuating said radially movable member by the use of a different key.
- 10 9. In a lock, a hollow door knob including two separable parts, means for causing said parts to be engageable and disengageable by rotation of one relatively to the other, a cylinder within said knob, a plug within said cylinder, and means actuated by said plug for locking a door and for locking the parts of said knob together.
- 15 10. In a lock, a hollow door knob including two separable parts, means for causing said parts to be engageable and disengageable by rotation of one relatively to the other, a cylinder in said knob, a plug in said cylinder, said plug including two relatively movable parts, and means actuated by one of said relatively movable parts for locking the parts of said knob together.
- 20 11. In a lock, a hollow door knob including two separable parts, a substantially radially movable member for locking said parts together, and a cylinder lock within said knob, said lock being operable to lock a door and also to actuate said radially movable member.
- 25 12. In a lock, a hollow door knob including two separable parts, a substantially radially movable member for locking said parts together, a lock cylinder within said knob, a plug within said cylinder, and means actuated by said plug for locking a door and for actuating said radially movable member.
- 30 13. In a lock, a hollow door knob including two separable parts, a substantially radially movable member for locking said parts together, a cylinder in said knob, a plug in said cylinder, said plug being formed in two relatively movable parts, and means actuated by one of said relatively movable parts for actuating said radially movable member.
- 35 14. In a lock, a hollow door knob including two separable parts, a substantially radially movable member for locking said parts together, and key-operable means within said knob for operating a door locking means by the use of one key and for actuating said radially movable member by the use of a different key.
- 40 15. In a lock, a support including two separable parts, a substantially radially movable member for locking said parts together, and a cylinder lock within said support, said lock being operable to lock a door and also to actuate said radially movable member.
- 45 16. In a lock, a support including two separable parts, a substantially radially movable member for locking said parts together, a lock cylinder within said support, a plug within said cylinder, and means actuated by said plug for locking a door and for actuating said radially movable member.
- 50 17. In a lock, a support including two separable parts, a substantially radially movable member for locking said parts together, a lock cylinder within said support, a plug in said cylinder, said plug being formed in two relatively movable parts, and means actuated by one of said relatively movable parts for actuating said radially movable member.
- 55 18. In a lock, a support including two separable parts, a substantially radially movable member for locking said parts together, a lock cylinder within said support, and key-operable means within said cylinder for operating a door locking means by the use of one key and for actuating said radially movable member by the use of a different key.
- 60 19. In a door lock, a cylinder lock, a support therefor comprising two separable parts engageable by a relative rotation thereof, means to lock said parts against rotation when said means is in one position and to release said parts for rotation when in another position, said cylinder lock co-operating with said means to positively shift the same to the releasing position.
- 20 20. A hollow knob including two separable parts to permit a key operable lock mechanism to be inserted into and removed from the interior of said knob, said parts being separable by the rotation of one relatively to the other, means for locking said knob parts against separation by rotation relatively to each other, and means movable by said lock mechanism and coacting with the means for locking said knob parts to operate the latter in one direction.
- 25 21. A hollow knob including two separable parts to permit a key operable lock mechanism to be inserted into and removed from the interior of said knob, said parts being separable by the rotation of one relatively to the other, means for locking said knob parts against separation by rotation relatively to each other, and means movable by said lock mechanism and coacting with the means for locking said knob parts to operate the latter in both directions.
- 30 22. A lock comprising a knob, a knob shank, a cylinder with a key plug contained within the knob, said knob and said shank being adapted to be fastened together by relative rotary movements, means for locking the shank and the knob against relative turning movements and means operative upon turning movements of the key plug relative to the knob for unlocking said locking means.

NORMAN B. HURD. 60
